(57) **CLAIM**

The ornamental design for film for packaging production, as
shown and described.

DESCRIPTION

FIG. 1 is a bottom plan view of the film for packaging production showing our new design; and,
FIG. 2 is a top plan view of the film for packaging production. The rounded rectangular section aligns with the similarly shaped section seen in FIG. 1.

The rectangular portion of the film that is seen in the center of the figures is formed as a double layer of material, as are the larger, irregularly shaped flanking regions. The film has a minimal thickness, and the increased thickness of the second layer would not be clearly distinct in a side view. The broken lines represent boundaries of the film and form no part of the claimed design. The dash-dot lines represent score lines cut in the film.
